UNITED STATES PATENT OFFICE.

THEADDEUS STEPHENS CASNER, OF PLAINFIELD, NEW JERSEY, ASSIGNEE, BY MESME
ASSIGNMENTS, TO GEORGE BAWAK, OF NEW YORK, N. Y.

CLOCK.

Application filed September 18, 1920, Serial No. 411,670. Renewed September 21, 1922. Serial No. 533,685.

To all whom it may concern:

Be it known that I, THADDEUS STEPHENS CASNER, a citizen of the United States, and residing at Plainfield, in the county of Union, State of New Jersey, have invented certain new and useful Improvements in Clocks, of which the following is a specification.

This invention relates to secondary clocks, and particularly to clocks of this class in which the hands are intermittently advanced by an electro-magnetic drive mechanism. Such clocks are usually designed and constructed so that the minute hand is advanced 10 through a minute's space at the end of each minute period of time, the hand moving forward in a fraction of a second through an entire minute space, or six degrees, as measured above the axis of the shaft as a center. This sudden jumping of the hands is objectionable, especially when the clocks are of 20 large size, and have long hands, being distracting to the eye and injurious to the clock mechanism.

It is the object of this invention to provide means for preventing this sudden jumping forward of the clock hands, in other words, to retard the movement of the hands, particularly of the minute hand, so that instead of jumping instantaneously through 30 an entire minute space when the clock mechanism is actuated, the hands will move slowly forward, the movement requiring several seconds or longer if desired, to be 35 completed. The invention will be fully disclosed in the following description when taken in connection with the accompanying drawings, in which—

Figure 1 is a top view of the well known 40 form of secondary clock mechanism having my invention incorporated therewith;

Figure 2 is a section on line 2—2 of Fig. 1; and

Figure 3 is a section on line 3—3 of Fig. 45 ure 1.

The invention may be incorporated with many forms of clocks, spring driven clocks, gravity operated clocks, and electrically driven clocks, and it will be understood that 50 while it is disclosed in combination with an electrically driven secondary clock, it is not limited in its application to this form alone. The clock illustrated has a minute shaft 10 which is rotatably mounted in the

frame and which supports the armature 11, escapement wheel 12, and inertia wheel 13, and also a pinion and gear of the usual reducing gearing R between the minute shaft and the hour sleeve 14. The escapement wheel 12 is rotatable with the shaft, but the armature 11 and the inertia wheel 13 are rotatable relatively to the shaft. An electro-magnet 15 secured to the rear of the frame has pole pieces 16, 16 at its ends which project forwardly and lie on opposite sides of the armature 11.

Located directly above and positioned parallel to the minute shaft 10 is an arbor 17, and on this arbor is pivotally supported a verge 18 having the usual locking and impulse pallets 19 and 20 respectively and also carrying at one end a driving dog 21, the upper end of which is pivoted to the verge and the lower end of which is adapted to enter successively the spaces between the teeth of the escapement wheel in the operation of the clock. A spring 22 having one end secured to arbor 17 and passing under a stud 23 secured to the verge, has its outer end pressing downwardly upon the upward end of the driving dog, and tends to keep the lower end of the dog in contact with the teeth of the escapement wheel at all times. The short shaft 24 extending transversely through the verge, upon the forward end of which the driving dog 21 is supported, extends rearwardly, as shown clearly in Figure 1, and a link 25 connects the rear end of this shaft with one end of the armature 11 so that the verge will be tipped about the arbor 17 when the armature is oscillated. A coiled spring 26 having one end connected to the armature and the other end to the frame of the clock, draws the armature to the position illustrated in Figure 3, whenever the electro-magnet is deenergized, further downward movement of the armature being prevented by the engagement of the pallet 20 with the escapement wheel.

The inertia wheel 13 is simply a relatively 100 heavy wheel, and is freely rotatable on the shaft. Rigidly connected thereto and also freely rotatably on the shaft is a small sleeve 27 having small gear or ratchet teeth, as illustrated in Figure 3. A flat member 28 has its upper end looped around the short shaft 24, and its lower end in a position to engage the teeth of member 27 and

a coiled spring 29 normally presses the lower end of this member against the ratchet teeth.

It will be seen that when the magnet is energized, the armature 11 will immediately assume a horizontal position, raising that end of the verge which carries the driving dog so that this dog passes over one tooth and engages the next higher notch. 10 The energization of the magnet is momentary, and when the current is cut off at the master clock, the spring 26 tends to immediately retract the armature and verge and to advance the escapement wheel one tooth, 15 to move the minute hand one space forward. In the upward motion of the verge, however, the lower end of member 28 has moved around the periphery of the toothed sleeve 27 and has engaged a tooth considerably 20 higher than the one with which it is illustrated in engagement in Figure 3 of the drawing. The return movement of the verge and armature shaft is opposed by the inertia wheel 13 which must be rotated by 25 the member 28 and because of the relatively heavy weight of this wheel and the comparative weakness of spring 26, a period of some seconds is required for this movement to take place. 30 In the clock mechanism illustrated, the inertia wheel is conveniently mounted on the minute shaft, but it will be obvious that it may be positioned at various points and is not limited in this respect. It may be 35 applied, as before stated, to clocks of various kinds and may in fact be made in other shapes if desired.

Having thus described the invention what I claim as new and desire to secure 40 by Letters Patent is:

1. In a clock mechanism, the combination of a minute hand and its supporting shaft, means to impart a step by step forward movement to said hand, and an inertia device arranged to control or regulate 45 said forward movements.

2. In a clock mechanism, the combination with a minute hand and its supporting shaft, of means to impart a step by step forward movement to said hand, an inertia 50 wheel, and means for engaging the minute hand with the inertia wheel during the movements of the hand to control or regulate said movements.

3. In a clock mechanism, the combination with a minute hand and its supporting shaft, of means to impart a step by step forward movement to said hand, an inertia wheel freely mounted on said shaft, and means for engaging the minute hand 60 with the inertia wheel during the movements of the hand to control or regulate said movements.

4. In a clock mechanism, a minute hand, means for imparting intermittent forward 65 movement to said hand, an inertia wheel free to turn but normally at rest, and devices for connecting said means to said inertia wheel to restrain and control the forward movement of the hand. 70

5. In a clock mechanism, a minute hand, means for imparting intermittent forward movement to said hand, an inertia wheel free to turn but normally at rest, and 75 ratchet mechanism for connecting said means to said inertia wheel to restrain and control the forward movements of the hand.

In testimony whereof I affix my signature.

THADDEUS STEPHENS CASNER.
